VAPORIZER FOR USE WITH ELECTRIC FANS.

1,113,146.

Specification of Letters Patent.

Patented Oct. 6, 1914.

Application filed August 30, 1912. Serial No. 717,938.

To all whom it may concern:

Be it known that we, JOHN E. STRATFORD and JOHN A. ACKLEY, citizens of the United States, residing at Houston, in the county of Harris and State of Texas, have invented certain new and useful Improvements in Vaporizers for Use with Electric Fans, of which the following is a specification.

10 Our invention relates to new and useful improvements in diffusers.

The object of the invention is to provide a device of the character described to be used in connection with the ordinary electric fan for the purpose of purifying, cooling and humidifying the air and to evaporate liquid of antiseptic or medicinal properties and diffuse the same through the atmosphere.

15 This device is adapted particularly to be used in theaters, auditoriums, and other rooms where people are accustomed to assemble together and where it consequently becomes particularly desirable to keep the 20 room supplied with fresh and wholesome air.

With the above and other objects in view, the invention has particular relation to certain novel features of construction, operation and arrangement of parts, an example 25 of which is given in this specification and illustrated in the accompanying drawings, wherein—

Figure 1 is a front elevation of an ordinary 30 electric fan, showing the diffuser attached thereto. Fig. 2 is a sectional side elevation of the diffuser taken on the line *a—a* of Fig. 3, and Fig. 3 is a sectional end view of the diffuser taken on the line *b—b* of Fig. 2.

40 Referring now more particularly to the drawings, the numeral 1 refers to the supporting stand of the fan which carries the motor 2 which is operatively connected with the blades 3 and rotates the same in the ordinary manner. These blades are surrounded and protected by the wire cage 4. The electric fan in all of its parts is of the well known and usual construction.

45 The diffuser proper consists of the reservoirs 5 and 6 and the intermediate open-work cage 7. The reservoir 5 is an oblong member, having inclosed bottom, sides and ends and whose top 8 is hinged thereto so as to be readily opened and closed. The sides 55 of the reservoir are held at a uniform dis-

tance apart and firmly braced by means of cross braces 9 which also divide the same into three compartments, substantially uniform in size. The ends of the reservoir 5 extend downwardly below said reservoir and 60 form also the outer ends of the reservoirs 6 and the cage 7. The reservoirs 6 have suitable bottoms, ends and sides, but have open tops. The cage 7 is formed of the end members hereinbefore referred to and 65 a plurality of metallic strips 10 secured to each side of said end members and arranged at a uniform distance apart so as to allow free passageway for the air therebetween. The inner ends of the reservoirs 6 are 70 formed of an arcuate member 11, which is so shaped as to readily fit down over the motor 2 of the fan. Near one side of the reservoir 5 is a partition 12 which extends from end to end thereof and from the bottom up to a 75 point near the top, leaving a narrow passageway between said partition and the rear side of said reservoir and this passageway is aligned with an oblong slot in the bottom of said reservoir. This passageway and slot 80 are provided for the passage of wicks therethrough, as will presently be described. A plurality of wicks are preferably used, and as shown, are arranged in pairs, designated, respectively, by the numerals 13 and 14. 85 The wicks 13 have their lower ends suspended down into the reservoirs 6 and extend upwardly through the cage 7 and through said slot and passageway and their upper ends extend over the upper edge of 90 the partition 12 and are secured thereover by means of clasps 15, while the wicks 14 are secured over said partition 12 by means of clasps 16, in such a manner that one end of said wicks will depend into the reservoir 95 5 and the other end will pass down through said space and slot into the bottom of said reservoir and hang suspended in the cage 7, said depending ends falling short of the reservoirs 6.

100 The operation of our device is as follows: The diffuser is secured upon the motor so that the arcuate member 11 will partially embrace the same and to the front side of the reservoir 5 are secured hooks 17 which 105 engage over the wire cage 4. The antiseptic fluid which is desired to be diffused is then poured into the reservoir 5 and is taken up by the wicks 14 by means of capillary attraction and carried over the partition 12 110

and gradually moves down said wicks and drops off of the free ends thereof into the reservoirs 6 and accumulates in said reservoirs until it rises therein and comes in contact with the lower ends of the wicks 13. From said reservoirs the liquid is taken up by capillary attraction by the wicks 13 and held in suspension in said wicks. It will, therefore, be observed that by use of the wicks 13 a greater quantity of fluid will be exposed to the air current than will be the case if only the wicks 14 are employed and yet the wicks 13 do not hasten the emptying of the reservoir 5, inasmuch as the upper ends are not in contact with the liquid therein. The fan creates a current of air and a consequent suction through the cage 7. The air passing through the cage, comes in contact with the wicks which are laden with the liquid and will absorb from the wicks a certain portion thereof and diffuse the same through the air current, which is driven off from the motor and circulated throughout the room, in which the same is placed.

25 What we claim is:-

1. In a vaporizer of the character described having an arcuate portion in the lower side thereof, the combination with a plurality of fluid reservoirs, arranged in fixed position, one above the other, an open cage between said reservoirs, strips across said open cage, a plurality of wicks, whose upper ends extend into the upper reservoir and whose other ends are suspended in said cage above the lower reservoir, a plurality of wicks secured to the upper reservoir, whose lower ends extend into the lower

reservoir, a frame work upon which said cage is mounted and means for securing said vaporizer upon the motor of a fan.

40

2. In a vaporizer, a frame having a portion of the bottom thereof arcuate and adapted to fit over a fan motor, said frame comprising a plurality of fluid reservoirs arranged in fixed position, one above the other, an open latticed cage between said reservoirs, a plurality of wicks for conducting fluid from one reservoir to the other and secured to the upper reservoir and means for securing said vaporizer upon the rear of the frame of a motor fan.

45

3. In a vaporizer, the combination with a frame having a portion of the bottom thereof arcuate and adapted to fit over a fan motor, said frame comprising a plurality of fluid reservoirs arranged in fixed position, one above the other, an open latticed cage between said reservoirs, a plurality of wicks for conducting fluid from one reservoir to the other and secured to the upper reservoir and means for securing said vaporizer upon the rear of the frame of a motor fan in such manner that when the fan is operated air will be drawn through said vaporizer.

50

In testimony whereof we have signed our names to this specification in the presence of two subscribing witnesses.

JOHN E. STRATFORD,
JOHN A. ACKLEY.
